UNITED STATES PATENT OFFICE

2,531,214

ELECTRICAL RESONATOR

Norman Leslie Harris, Hatch End, and John Walter Ryde, Northwood, England, assignors to M. O. Valve Company Limited, a corporation of Great Britain

Application January 4, 1947, Serial No. 720,286
In Great Britain April 22, 1940

Section 1, Public Law 690, August 8, 1946
Patent expires April 22, 1960

11 Claims. (CL 178—44)

1

This invention relates to electric resonators of the type comprising a metallic wall, closed except for one or two apertures and so shaped that the field within the wall can be excited to oscillations, whose frequency depends on the shape and size of the resonator.

An object of the invention is to provide an electric resonator which may be altered in shape and dimensions upon application of heat and thereby its natural frequency changed or adjusted.

Another object of the invention is to provide an electric resonator which will maintain a constant frequency under varying temperatures tending to alter its natural frequency.

A particular advantage of the invention is that simple heat responsive elements may be fitted to the resonators for adjustment of the effective resonant frequency.

Another advantage of the invention is that resonators constructed in accordance therewith are thermally stable and self-compensating as to resonant frequency.

Other objects and advantages will be apparent from the following description of the invention, defined in particularity in the appended claims and taken in connection with the accompanying drawing in which:

Figure 1 is an elevational view in cross section of a resonator having means external to the resonator to adjust its effective resonance upon application of heat;

Figure 2 is an elevational view in cross section of a modified form incorporating the heat responsive element within the body of the resonator;

Figure 3 is a partial top view taken along line 3—3 of Figure 2;

Figure 4 is a perspective view of another embodiment of the invention, and

Figure 5 is a partial view in cross section taken along line 5—5 of Figure 4.

Broadly the invention contemplates the construction of an electric resonator of the cavity type in various forms with one or more flexible or deformable parts which when acted upon by a suitably directed force will change the dimensions and effective resonance of the resonator. These parts in accordance with the invention are actuated by a heat responsive element such as a bimetallic member or the parts themselves may be made of bimetal and become distortable upon application of heat.

The thermal distortable part or member may serve either of two purposes or both of them.

2

One is to maintain the natural frequency constant in spite of thermal expansion or contraction in the rest of the apparatus, due to changes in ambient temperature, or to the heating of the resonator by the energy dissipated in it when it oscillates; then no heater is required. This purpose may be usefully served whether the resonator is or is not enclosed in a sealed envelope. The other purpose is to change deliberately the natural frequency of the resonator, then a heater through which electric current can be passed must be associated with the part or member. This second function is most useful when the resonator is enclosed in a sealed envelope.

15 For the purpose of illustrating the application of the invention to cavity type resonators, a toroidal form was chosen as a representative type, being widely used in certain electron discharge devices. It will be clear that the invention is 20 applicable as well to resonators of other geometrical form.

25 Resonators of the type shown are often placed in an evacuated space when they form part of an electron discharge device and the means herein shown for controlling their resonant frequency is particularly suited for such conditions. For the sake of simplicity, the evacuated space is not outlined in the drawing in view of the fact that it is not essential as far as the operation of the invention is concerned.

30 Referring to the drawing in Figure 1, the resonator comprises the toroidal shell 6 which by its particular configuration encloses a toroidal cavity narrowed in the center between the parallel walls 7 and 8. A central aperture 9 is provided for the excitation of the resonator. In accordance with the invention there is provided a flexible disc-shaped wall member 10 which is placed inside the resonator and attached to the inner wall in such manner as to be in alignment with the parallel walls 7 and 8. An aperture 11 in the member 10 is also aligned with the aperture 9 of the resonator so as not to impede the passage of charged particles which may be utilized for exciting the resonator.

35 40 45 50 55 The flexible wall member 10 is in effect a movable extension of the parallel wall 8 and when moved axially with respect to the resonator will alter the effective space or distance between the walls 7 and 8. As is well known, this space is one of the determining factors of the resonant frequency of the resonator. To effect substantial movement of the member 10 a rod 12 enters the wall 8 through a suitable aperture 13 and is attached at one end to the member 10.

and at the other end to a strip 14 of heat responsive element which is secured to the resonator by means of a support 15. The strip 14 may be made of a bimetallic material or similar heat responsive element which flexes or deforms upon application of heat. The strip 14 is shaped in such manner that the motion thereof exerts a force on the rod 12 in either direction between the walls 7 and 8. A motion in the direction toward the wall 7 will decrease the resonant frequency of the resonator whereas a motion of the member 10 toward the wall 8 will increase the frequency.

From the above it can be seen that by proper proportioning of the strip 14 as to heat response, temperature compensation of the resonator may be obtained and a desired resonant frequency maintained while ambient temperature variations occur during operation. On the other hand, the resonant frequency may be deliberately changed at will by providing heating means for the strip 14 such as an electric heating element 16 connected to wires 17 and 18 through which current may be applied.

In Figures 2 and 3 the modification resides in the flexible member 10 which in itself forms one of the parallel walls and is a disc with radially oriented slots 19. The segments 20 so produced are composed of bimetallic elements which flex inwardly upon application of heat. The heating element 16 is placed under the disc 10, that is, under the bottom parallel wall of the toroid.

The modification shown in Figure 4 is particularly suitable where compensation is desired for ambient temperature variations. The resonator is made up of two semi-toroidal halves of conducting plates 6 and 6' peripherally joined together. A series of slots 21 are cut in a radial direction dividing the resonator into a number of segments which possess sufficient resiliency for appreciable elongation in the direction normal to the axis of the resonator. Bimetallic heating strips 14 are tightly secured for example by welding to the upper and lower halves of the resonator at each segment. This is shown in the partial section of Figure 5. The strips 14 tend to flex inwardly with respect to the resonator in proportion to temperature increase and cause elongation of the segments which counterbalances the normal expansion of the resonator when the temperature is increased. The reverse condition arises when the temperature decreases.

We claim:

1. A high frequency electric resonator comprising a closed conducting body of toroidal shape enclosing a cavity having dimensions determining a normal resonant frequency, said resonator having in the center spaced parallel walls normal to the axis, a flexible member within said body and having a first portion attached to said resonator adjacent one of said walls and having a second portion movable toward the other of said walls whereby the effective space between said second portion and said other wall and thereby the resonant frequency of said resonator may be altered, and heat responsive means for causing substantial movement of said second portion of said member in accordance with temperature variations.

2. A high frequency electric resonator comprising a closed conducting body of toroidal shape enclosing a cavity having dimensions determining a normal resonant frequency, said resonator having in the center spaced parallel walls normal to the axis, a flexible member within said

body and having a first portion attached to said resonator adjacent one of said walls and having a second portion movable toward the other of said walls whereby the effective space between said second portion and said other wall and thereby the resonant frequency of said resonator may be altered, and heat responsive means comprising a strip of bimetallic element affixed at one end to said resonator and at the other end to said second portion of said member for causing substantial movement of said second portion in accordance with temperature variations.

3. A resonator in accordance with claim 2, further including means for heating said bimetallic element.

4. A high frequency electric resonator comprising a closed conducting body of toroidal shape enclosing a cavity having dimensions determining a normal resonant frequency, said resonator having in the center spaced parallel walls normal to the axis, one of said walls being flexible and having a portion movable toward the other of said walls whereby the effective space between said walls and the resonant frequency of said resonator may be altered, and heat responsive means for flexing said wall in accordance with temperature variations.

5. A resonator in accordance with claim 4 wherein said heat responsive means comprises strips of bimetallic elements forming said flexible wall.

6. A resonator in accordance with claim 5, further including means for heating said bimetallic elements.

7. A high frequency electric resonator comprising a closed conducting body of toroidal shape enclosing a cavity having dimensions determining a normal resonant frequency, said body having in the center a pair of spaced parallel walls

normal to the toroidal axis, a flexible member having a peripheral portion attached to said resonator adjacent one of said walls and a central portion disposed between said walls and movable toward the other of said walls whereby the effective space between said central portion and said other wall and thereby the resonant frequency of said resonator may be altered, and heat responsive means for causing substantial movement of said central portion in accordance with temperature variations.

8. A resonator according to claim 7, wherein said heat responsive means comprises a strip of bimetallic element affixed at one end to said resonator and at the other end to said central portion of said flexible member, and means for heating said element.

9. A high frequency electric resonator comprising a conducting body enclosing a cavity having dimensions determining a normal resonant frequency, said dimensions and resonant frequency being subject to changes due to ambient temperature variations, and means for automatically compensating for said changes to maintain the desired resonant frequency comprising at least

one deformable flexible element forming a portion of the wall of said body and adapted upon deforming to alter said dimensions and resonant frequency and means responsive to ambient temperature variations for flexing said flexible wall element in opposition to said changes.

10. A high frequency electric resonator comprising a pair of circular conducting plates peripherally attached to each other and forming a toroidal body enclosing a cavity having dimensions determining a normal resonant frequency,

said dimensions and resonant frequency being subject to changes due to ambient temperature variations, and means for automatically compensating for said changes to maintain the desired resonant frequency comprising a plurality of radially-directed slits formed in said plates dividing said plates into resilient segments, a bimetallic element on each segment, said elements being adapted to flex said segments in response to ambient temperature variations to alter said dimensions and resonant frequency in opposition to said changes.

11. A high frequency electric resonator comprising a conducting body enclosing a cavity having dimensions determining a normal resonant frequency, said dimensions being subject to changes due to ambient temperature variations, said body having in the center a pair of spaced parallel walls, one of said walls being flexible and having a portion movable toward the other 20 of said walls whereby the effective space between said walls and the resonant frequency of said

5 resonator may be altered, and means responsive to ambient temperature variations for flexing said flexible wall in opposition to said changes to automatically compensate for said changes and maintain the desired resonant frequency.
